(57) CLAIM

The ornamental design for a digital audio disc player, as shown and described.

DESCRIPTION

FIG. 1 is a perspective view of the front, right side and bottom of a digital audio disc player showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a perspective view in the condition of the power being turned on thereof.

The broken line showing on FIG. 8 is for illustrative purposes only and forms no part of the claimed design.

1 Claim, 6 Drawing Sheets
